JOHN R. BINGAMAN, OF WEST READING, PENNSYLVANIA

LOCK-SWITCH MECHANISM

Application filed June 6, 1927. Serial No. 196,762.

My invention relates to locking mechanism in which the key rotation merely positions the movable key-controlled element for subsequent completion of such movement only upon withdrawal of said key from the lock, my object being to require such removal of the key, to prevent its deliberately or inadvertently remaining in the lock after operation for unauthorized later use. Such locking mechanism may be found useful for a number of purposes, but is particularly applicable to the ignition switch mechanism of an automobile, where the requirement that the key be removed before ignition can be completed, is specially of value, as it insures against the key being in the lock when the car is stopped for ready operation by the joy-rider thief.

With this main object in view, and with other objects that will appear later as the description proceeds, my invention comprises the improved structure hereinafter fully described in connection with the drawings accompanying the same and forming part thereof, the novel features thereof being particularly set forth in the appended claims.

The drawings show a preferred embodiment of my invention, as applied specifically to the ignition switch mechanism of an automobile, for which, among other uses, it is readily applicable, and indicate in,—

Fig. 1 a sectional elevation of a switch box embodying my improved lock mechanism, the section being taken on the line 1—1 of Fig. 2.

Fig. 2 a cross-sectional view of the same taken on the line 2—2 of Fig. 1; some of the parts being shown differently positioned for the purpose of clearness.

Fig. 3 a longitudinal sectional view thereof on the line 3—3 of Fig. 1, but with a different key position.

Figs. 4, 5 and 6, diagrammatic showings respectively of three main positions of operation.

Fig. 7 a modification within the scope of the invention, showing a lock bolt in place of the switch element indicated in Figs. 1 to 6.

Referring now particularly to the showing in Figs. 1 to 6 of the drawings, in which like figures of reference refer to like parts, 5 indi-

cates any suitable box adapted to contain the ignition switch mechanism for an automobile, and which usually comprises, as indicated, two spaced contact elements 6 and 7, connected in known manner by wires 8 and 9 to the usual electrical system, and an ignition opening and closing switch element 10, shown pivotally mounted at 11 and having arms 12 and 13 provided with ends 14 and 15 adapted to be swung into and out of engagement respectively with contacts 6 and 7; the box 5, for insulating purposes, being preferably formed of non-conducting material, as bakelite, hard rubber, or the like. Such generally known ignition switch mechanism has heretofore commonly been operated as by a hand lever, to engage and disengage said contacts; and where a lock device has been employed, the key controlled said switch by turning movement only, and could remain in the lock at all times irrespective of whether or not the electric circuit was open or closed. In my improved lock mechanism now about to be described in detail, such inadvertent or deliberate leaving of the key in the lock is impossible, as ignition cannot be completed without its removal, and replacement of the key during such switch engagement is made impossible.

In the drawings I have indicated a cylinder lock 20 of any known construction, operated by a key 21, as usual, to free the rotatable cylinder 22 from the tumbler pins 23, said cylinder carrying a cam 24 adapted to contact with an arm 25, preferably of non-conducting material, extending radially from switch 10 so as to rotate the latter in one direction; reverse swinging of said arm 25 in the present instance, being effected by a hand lever 26 having an extended pivot stem 27 carrying a cam 28 rotatable in the plane of arm 25. In this lock, as heretofore, the key 21 may be inserted and withdrawn only when the tumbler pins of the lock 20 and rotatable cylinder 22 are in register, and when said cylinder is partly rotated as in Fig. 1, said pins, indicated by dotted lines, are out of register and those in the cylinder engage the recessions in the edge of the key to prevent its withdrawal, as well understood. The lock 20 is shown as

mounted in a cylindrical extension 30 of the rear casing wall, with lock cam 24 opposite a cut-out portion of said extension, indicated at 31 in Fig. 2, through which latter the switch arm 25 extends into the throw of cam 24 when in one extreme of its swing. And to insure positive action of said switch 10 and its retention in either extreme of its swing, I provide as shown, a flexible device 35, preferably in the form of a coil spring, with its ends engaging respectively a radial post 36 on switch 10, and a fixed post 37 on the casing wall: said spring being reversely flexed, as indicated in dotted line showings, by the swinging movement of switch 10, so that its torque acts to restrain the switch against turning movement until the post 36 passes the dead center of its travel, when said torque acts to continue such switch turning movement.

20 To require removal of the key before its controlled element can complete its movement started by such rotation, I have indicated in the specific showing of the drawings, a contact guard 40, preferably of non-conducting material, carried on the end of a lever 41, intermediately pivoted at 42, so that said guard may swing above contact 7 into the arc of travel of switch arm end 15, to limit the swing of said switch short of engagement with its contacts 6 and 7, but under pressure of spring 35, duly flexed by such preliminary switch movement, and ready to effect further contact-engaging swing to the switch upon withdrawal of guard 40 from its arc of swing.

30 Lever 41 is, as shown, oscillated by a lever 43 pivoted at 44 and having a pin 45 engaging an inclined slot 46 in the lower end of lever 41. And lever 43 is operated by the key 21, in the preferred construction shown, through a special pin 50 extending into the key way and acting in a manner similar to the tumbler pins 23, but preferably bearing on the opposite straight under edge of said key, and furthermore said pin 50 is preferably so located in said way as to practically require full withdrawal of the key in order to free said pin from key action thereon. Said pin 50, as shown, is connected to lever 43 by a pivot 51, and extends through aligned apertures in the extension 30 and lock casing 22 to engage in a recess 53 therefor in the key way of cylinder 22; and when said pin is seated in said recess 53, insertion of the key acts thereon to swing lever 43, and, through lever 41, move guard 40 to position over contact 7 and into the path of travel of switch arm end 15 which latter comes to rest on said guard. Removal of the key from its way, frees pin 50 and levers 43 and 41 and guard 40 for reverse movement, thus permitting spring 35 to further swing switch 10 to engagement with contacts 6 and 7; springs 54 acting on lever 41, and 55 acting on lever 43, insuring such quick reverse movements.

55 Cylinder 22 is further shown with a partial

circumferential recess 56 in which the key-depressed pin 50 rides to limit rotation of cylinder 22 except as required to effect the aforesaid initial swinging movement of switch 10. It will be understood that after cylinder 22 is partly rotated by its key 21, said cylinder is reversely rotated to the starting point so that the key may be withdrawn, such reversing movement having no effect on switch 10, as the latter has, by such first cylinder rotation, been swung sufficiently to tension spring 35 to hold it and exert further turning pressure on said switch. When the switch has been swung into engagement with its contacts 6 and 7, by spring action upon withdrawal of guard 40 as effected by the key removal, the latter may not again be inserted into its way until the switch has been reversely swung by hand lever 26, as lever end 15 then lies in the path of guard 40 and prevents any swing thereof, and consequently the pin 50 is prevented from moving, thus blocking the way against introduction of said key. Proper insulation of the electric circuit, it will be noted, is simply provided for by making the casing 5, arm 25, and contact guard 40, of non-conducting material as stated.

In the diagrammatic views: Fig. 4 clearly indicates the open switch position, with key removed and switch closing movement prevented by the locked cylinder 22. Fig. 5 indicates the initial movement effected by rotation of the inserted key, guard 40 being now moved to close contact 7, and spring 35 reversely flexed. Fig. 6 shows the completed switch movement into contact engagement, effected by tension of spring 35 upon reverse swing of guard 40 as effected only by the key removal from the lock.

It will be clearly understood from the foregoing description, that my main object of requiring removal of the key from the lock to complete its key-controlled element movement, is accomplished in a simple and effective manner; and for the particular application to an automobile ignition switch mechanism, insures that the key may not inadvertently remain in the lock while the engine is running, but is required to start ignition, and furthermore said ignition is locked in idle position without further action upon turning of hand lever 26 to reverse said switch movement.

As my improvements relate to the locking mechanism, and not to the switch construction, I have not attempted to show the required insulation of the switch elements, it being understood that due provision therefor may be readily provided as heretofore. And furthermore to prevent ready cutting and splicing of the ignition wires outside of the thus effectively locked switch box, I have shown these wires as extending through heavy protecting tubes, which, in connection

with due care in securely affixing the box to the automobile, will deter unauthorized tampering with the latter by any but the most determined thief supplied with a kit of tools.

5 It will be readily understood that the mechanism above described may be used for other purposes than controlling an ignition switch mechanism; for instance, in Fig. 7, I have indicated a locking bolt 70, or the like, 10 in place of switch 10, and also indicate a key-actuated lock lever 71 that positively prevents any preliminary bolt movement to be effected by key rotation, such latter movement merely flexing a spring 72 so as to tension it to act 15 in moving said bolt when the key is removed to disengage said lock lever 71. A hand lever 73 may be used to retract said bolt and thus reversely flex said spring.

Having thus fully described my invention, 20 and the manner of its operation, I do not desire to limit myself to the specific embodiments above set forth in detail, as other modifications may be devised within the scope and spirit of my invention as defined in the following claims.

What I claim as my invention, and desire to secure by Letters Patents, is:

1. A lock switch mechanism comprising a contact element, a movable switch element engageable therewith, means to obstruct engagement of the switch element with the contact element, a lock, means actuated by the lock for moving the switch element toward the contact element, said lock having a keyway, 35 a movable key obstructing element extending into the keyway of the lock, a key insertable into the keyway for actuating the lock, means operatively connecting the key obstructing element to the first mentioned obstructing means, whereby movement of the lock by the key causes initial movement of the switch element toward the contact element, and withdrawal of the key causes the key obstructing element to project into the keyway 40 to withdraw the first mentioned obstructing means from the path of movement of the switch element, to allow the latter to engage said contact element, and spring means for automatically moving the switch element into engagement with the contact element when the obstructing means has moved out of obstructing position.

2. A lock switch mechanism comprising a contact element, a movable switch element engageable with the contact element, a key type lock for initiating movement of the switch element toward the contact element, said lock having a keyway, a movable obstructing member extending into the keyway, 55 a key for the lock, said obstructing member movable under the influence of the key when the latter is inserted in the keyway, a switch obstructing member movable into the path of movement of the switch element, means connecting the obstructing members for caus-

ing the switch obstructing member to move into obstructing position when the key is inserted in the keyway, means cooperating with the connecting means for moving the key obstructing member into the keyway and the 70 switch obstructing member out of the path of movement of the switch element when the key is withdrawn from the keyway, and spring means for moving the switch element into engagement with the contact element when the switch obstructing member is moved out of obstructing position.

3. A lock switch mechanism comprising a contact element, a movable switch element engageable with the contact element, a key type lock for initiating movement of the switch element toward the contact element, said lock having a keyway, a movable obstructing member extending into the keyway, a key for the lock, said obstructing member movable under the influence of the key when the latter is inserted in the keyway, a switch obstructing member movable into the path of movement of the switch element, means connecting the obstructing members for causing the switch obstructing member to move into obstructing position when the key is inserted in the keyway, means cooperating with the connecting means for moving the key obstructing member into the keyway and the switch obstructing member out of the path of movement of the switch element when the key is withdrawn from the keyway, and spring means for moving the switch element into engagement with the contact element when the switch obstructing member is moved out of obstructing position.

4. A lock switch mechanism comprising a contact element, a movable switch element engageable with the contact element, a key type lock for initiating movement of the switch element toward the contact element, said lock having a keyway, a movable obstructing member extending into the keyway, a key for the lock, said obstructing member movable under the influence of the key when the latter is inserted in the keyway, a switch obstructing member movable into the path of movement of the switch element, means connecting the obstructing members for causing the switch obstructing member to move into obstructing position when the key is inserted in the keyway, means cooperating with the connecting means for moving the key obstructing member into the keyway and the switch obstructing member out of the path of movement of the switch element.

when the key is withdrawn from the keyway, spring means for moving the switch element into engagement with the contact element when the switch obstructing member is moved out of obstructing position, and manually operated means for initiating movement of the switch element away from the contact element.

5. A lock switch mechanism comprising a contact element, a movable switch element engageable with the contact element, a key type lock for initiating movement of the switch element toward the contact element, said lock having a keyway, a movable obstructing member extending into the keyway, a key for the lock, said obstructing member movable under the influence of the key when the latter is inserted in the keyway, a switch obstructing member movable into the path of movement of the switch element, means connecting the obstructing members for causing the switch obstructing member to move into obstructing position when the key is inserted in the keyway, means cooperating with the connecting means for moving the key obstructing member into the keyway and the switch obstructing member out of the path of movement of the switch element when the key is withdrawn from the keyway, spring means for moving the switch element into engagement with the contact element when the switch obstructing member is moved out of obstructing position, and a hand operated cam engageable with the switch element for initiating movement of the latter away from the contact element.

6. A lock switch mechanism comprising a contact element, a movable switch element engageable with the contact element, a key type lock for initiating movement of the switch element toward the contact element, said lock having a keyway, a movable obstructing member extending into the keyway, a key for the lock, said obstructing member movable under the influence of the key when the latter is inserted in the keyway, a switch obstructing member movable into the path of movement of the switch element, means connecting the obstructing member for causing the switch obstructing member to move into obstructing position when the key is inserted in the keyway, means cooperating with the connecting means for moving the key obstructing member into the keyway and the switch obstructing member out of the path of movement of the switch element when the key is withdrawn from the keyway, and spring means for moving the switch element into engagement with the contact element when the switch obstructing member is moved out of obstructing position, the means connecting the obstructing members comprising a lever having its medial portion mounted on a fixed pivot, the switch obstructing member being secured to one end

of said lever, the opposite end portion of the lever having an inclined slot, a second lever having one of its ends mounted on a fixed pivot, a pin at the opposite end of the second lever slidably engaging the slot, the key obstructing member being pivotally mounted on the second lever.

7. A lock switch mechanism comprising a contact element, a movable switch element engageable with the contact element, a pin tumbler type lock having a keyway and provided with a movable element engageable with the switch element for initiating movement of the latter toward the contact element, a movable key obstructing member projecting into said keyway, a key insertable into the keyway and engageable with said obstructing member for moving the latter away from the keyway, said key acting to operate the movable member of the lock under the influence of the operator for initiating movement of the switch element toward the contact element, a switch obstructing member movable into and out of the path of movement of the switch element, means operatively connecting the obstructing members for causing the switch obstructing member to move into obstructing position when the switch obstructing member is moved away from the keyway by the insertion of the key in the latter, means cooperating with said connecting means for moving the key obstructing member into the keyway, and the switch obstructing member out of obstructing position when the key is withdrawn from the keyway, and spring means for moving the switch element into engagement with the contact element when the switch obstructing member has been moved out of obstructing position.

8. A lock switch mechanism comprising a contact element, a movable switch element engageable with the contact element, a pin tumbler type lock having a keyway and provided with a movable element engageable with the switch element for initiating movement of the latter toward the contact element, a movable key obstructing member projecting into said keyway, a key insertable into the keyway and engageable with said obstructing member for moving the latter away from the keyway, said key acting to operate the movable member of the lock under the influence of the operator for initiating movement of the switch element toward the contact element, a switch obstructing member movable into and out of the path of movement of the switch element, means operatively connecting the obstructing members for causing the switch obstructing member to move into obstructing position when the switch obstructing member is moved away from the keyway by the insertion of the key in the latter, means cooperating with said connecting means for moving the key

obstructing member into the keyway, and the switch obstructing member out of obstructing position when the key is withdrawn from the keyway, spring means for moving the switch element into engagement with the contact element when the switch obstructing member has been moved out of obstructing position, and a hand operated member for initiating movement of the switch element away from the contact element, said spring means functioning to complete the movement of the switch element away from the contact element.

9. A lock switch mechanism comprising a casing, a switch element pivotally mounted in the casing, stationary contact elements to be engaged by the switch element, a tumbler type cylinder lock mounted in the casing and having a rotatable plug, a cam connected to the plug and engageable with the switch element for initiating movement of the latter toward the contact elements, said plug having a keyway, a reciprocating obstructing member projecting into said keyway, a key for the lock insertable into the keyway and engageable with the obstructing member for moving the latter away from the keyway, a switch obstructing member movable into and out of the path of movement of the switch element, a first lever having its medial portion pivotally mounted in the casing, the switch obstructing member being united with one end of said lever, the opposite end portion of the lever having an inclined slot, a second lever having one of its ends pivotally mounted in the casing, a pin at the opposite end of the second lever slidably engaging said slot, a pin pivotally connecting the key obstructing member to the second lever, a spring engaging the second lever for forcing the key obstructing member into the keyway, a fixed post in the casing, a post projecting radially from the pivoted switch element, and a spring interposed between and engaging said post for completing oscillatory movements of the switch element, and a hand operated element engageable with the switch element for moving the same away from said contact elements.

50 In testimony whereof I affix my signature.
JOHN R. BINGAMAN.
